(57) **CLAIM**

The ornamental design for a shoe sole, as shown and described.

DESCRIPTION

FIG. 1 is a medial side view of a shoe sole;
FIG. 2 is a bottom view of the shoe sole;
FIG. 3 is a lateral side view of the shoe sole;
FIG. 4 is a top view of the shoe sole;
FIG. 5 is a front view of the shoe sole;
FIG. 6 is a rear view of the shoe sole; and,
FIG. 7 is a perspective view of the shoe sole.
A shoe sole is shown in FIGS. 1-7. Dashed lines have been included for illustrative purposes only, and form no part of the claimed design.
